UNITED STATES PATENT OFFICE.

MICHELANGELO MARIA CARDELLINO, OF RACCONIGI PER CAVALLERLEONE, ITALY.

MAGNETO-ELECTRIC MACHINE.

1,405,275.

Specification of Letters Patent.

Patented Jan. 31, 1922.

Application filed October 24, 1919. Serial No. 332,873.

To all whom it may concern:

Be it known that I, MICHELANGELO MARIA CARDELLINO, a subject of the King of Italy, and resident of Racconigi per Cavallerleone, 5 in the Kingdom of Italy, have invented certain new and useful Improvements in Magneto-Electric Machines; and I do hereby declare the following to be a full, clear, and exact description of the invention, such as 10 will enable others skilled in the art to which it appertains to make and use the same, reference being had to the accompanying drawings, and to letters or figures of reference marked thereon, which form a part of 15 this specification.

The present invention relates to magneto-electric machines and consists in the novel arrangement of the magnetic circuits, whereby a great number of advantages are obtained, as compared to the known machines 20 of the same character.

The most important of said advantages are the following:

- (1) Maximum utilization of the magnetic 25 flux and minimum leakage;
- (2) Magnetic circuit is kept constantly closed, assisting in the maintenance of magnetism in the permanent magnets;
- (3) Windings fully independent from the 30 rotating part; weight and size of the whole reduced as compared to the usual machines of the same efficiency;
- (4) Great facility of construction of the 35 several parts and in the mounting and dis-

The machine can have a large number of different applications among which its employment as an ignition device in explosion engines, or as a call bell in telephonic 40 plants.

In the accompanying drawings—

Fig. 1. is a diagrammatic sectional view; taken through the axle of the two rotors of a magneto electric machine embodying my 45 invention;

Figs. 2 and 3 are two cross-sections of the machine if taken on line H. H. of Fig. 1 (in Fig. 3 the rotors are shown turned 90° from the position shown in Fig. 2);

Fig. 4 shows one of the laminated elements forming the shoe.

Fig. 5 shows diagrammatically the initial position of a rotor in the instant in which the longer axis of the permeable section is

on the diameter perpendicular to the central line of the pole shoes when said pole shoes have an angular amplitude of 55 90°.

Fig. 6 shows by an ideal broken line with sharp angles a diagram of the electro-motive force developed during a rotation of 60 180° accomplished by the rotor shown in Fig. 5.

Fig. 6^a shows the same diagram in which the edges have been rounded as the electromotive force is not absolutely steady or 65 absolutely zero during the intervals of variation of the flux.

Figs. 7 and 7^a show respectively the ideal 70 diagram and the diagram with rounded edges of the other rotor with a phase displacement of 90° with respect to the rotor shown in Fig. 5.

Figs. 8 and 8^a show respectively the sum 75 of the diagram of Fig. 6 reversed and the diagram of Fig. 7; and the sum of the diagram of Fig. 6^a reversed and the diagram of Fig. 7^a.

Fig. 9 shows diagrammatically the initial 80 position of a rotor at the moment in which the longer axis of its permeable section is on the central line of the polar shoes, when the latter are of an angular amplitude of 60°.

Figs. 10 and 10^a show, respectively, by an ideal broken line with sharp edges and a 85 broken line with rounded edges the diagram of the electromotive force developed during the rotation of 180° accomplished by the rotor shown in Fig. 9.

Figs. 11 and 11^a show, respectively, the 90 ideal diagram and the diagram with rounded edges of the other rotor having a phase displacement of 90° with respect to the rotor shown at Fig. 9.

Figs. 12 and 12^a show, respectively, the 95 sum of the diagrams Fig. 10, reversed with Fig. 11; and Fig. 10^a reversed, with Fig. 11^a.

1, 1, designate two permanent magnets having the form of cylindrical bars mounted 100 in parallel relation with similar polarities on the same side. These magnets constitute the main portion of the machine.

On both ends of said magnets for nearly two-fifths of their length are placed two sets 105 of soft iron shoe plates 3 which have an oval peripheral shape and are provided with two holes 1' for the passage of the mag-

nets therethrough. Two guide bolts 2 of diamagnetic material pass through holes 2' formed in said plates near their ends. The plates are also formed with two openings 4, placed symmetrically on an axis at right-angles to that of the holes 1' from which they are equidistant.

As it is clearly illustrated on Fig. 4 of the drawing, a portion of the outer edge of holes 10 4 is circular and projecting, thus forming a proper polar shoe element.

The complete shoe results from piling up a number of plates 3 like those described and illustrated in Fig. 4. The nuts 6 of the guide bolts press the iron-plate shoes 3 against the projection provided on the shank 7 or a spacing sleeve.

Moreover two rotors are provided, each formed by a set of soft iron plates 8 having 20 a lengthwise rectangular form, separated from each other by means of a thin insulating piece (like the ones used in the armature of the usual dynamo-electric machine), placed between two brass plates extending 25 on all the length of the sets of plates. For this purpose a brass bar can be employed which is provided with a longitudinal slot for the plate set 8. The latter is placed therein and then reduced on a lathe to the 30 same diameter as the bar. The whole of the plate set is turned together with the brass bar into a cylinder having throughout its length a diameter slightly shorter (by approximately $\frac{1}{4}$ of m/m) than that of the circular part of the outer edge of the holes 4 or distance between the poles.

On the ends of the rotors the journals and the control wheels 10 are attached. The axes of rotation of the rotors are parallel 40 to the axis of the magnet and are the centers of the holes 4. As it is clearly illustrated in Figs. 2 and 3, although the metallic section of the rotor is circular, the magnetic permeable section is a rectangle having the 45 shorter sides substituted by arcs.

The two rotors are exactly alike, and receive a synchronous movement by means of the wheels 10 keyed thereon at one end; they rotate with a phase displacement of a quarter of a turn to each other; that is to say when (as shown on Fig. 3) the core of one of the rotors (the lower one on said figure) is fully in front of the shoes or projections 5, the brass pieces of the other rotor, on the contrary, face the shoes in a position 90° from the other rotor.

Two fixed bobbins 11 and 12 are mounted on insulating spools *c* which surround the rotors in a free space, of nearly one-fifth of the length, formed between the two sets of plates 3. These spools are kept centered by two brass plates *d* formed with holes to receive the heads of the spools.

The machine works as follows: 65 In the position shown on Fig. 3, the whole

of the flux emanating from the poles of the two permanent magnets 1 is reversed on the rotor placed at the bottom of the figure, which shows the maximum magnetic section facing the shoes with the minimum gap, 70 which may be of $\frac{1}{4}$ of m/m.

On the contrary in the other rotor the minimum part of the flux can penetrate owing to the gap, which, according to the size of the figure, varies from $2\frac{1}{2}$ near the 75 polar horns, to 5 m/m (at the centre of the shoes) that is about 15 times the gap of the other rotor. If however any fly lines eventually penetrate from the polar horns into the iron of the upper rotor, it would be cut 80 by the insulators placed between the plates, which will warrant for the absence of flux in the said rotor.

The flux having entered the lower rotor from the north shoe (for instance from the 85 right one in Fig. 1) passes through the rotor longitudinally and closes at the opposite end through the small gap of the south shoe (that on the left of Fig. 1).

After $\frac{1}{4}$ of a turn both rotors have 90 reached the position shown on Figure 2. In the lower one the flux has passed from the highest value to null, and in the other rotor from null to its highest value. It must be pointed out that during the quarter of a 95 turn described the magnetic circuit has remained constantly closed and with the flux all on one side by the end positions, and the flux divided between the two rotors by the 100 middle positions.

During the following quarter of a turn the same variations in the flux take place, but in the reverse direction, between the rotors, that is from null to the maximum in the lower rotor and from maximum to null in the 105 upper one. During the second half turn the same course is exactly repeated as described for the first half turn.

During the full turn of the rotors, four 110 variations have then taken place, corresponding to two full periods of the current generated in the bobbins.

The flux is never reversed in the rotors but it is submitted to rapid pulsations. The current which is generated is of the alternating 115 type. It is remarkable that, by the same number of turns of the rotors of this machine, and of the double T-shaped armature of a usual bipolar magneto-electric machine, a current of double frequency is obtained. The ends of the windings will be connected in such a way as to sum up the electromotive forces which are at every moment produced in both bobbins and which have the same absolute value but the opposite polarity. 120

According to the control system, the rotors can either rotate in the same or in opposite direction, but this has no practical importance, since the working of the machine is the same in both cases. In the instance 130

which has been illustrated, the rotors are controlled by a central wheel 13 which engages with two cogged wheels 10 keyed on the axles of both rotors which turn consequently in the same direction.

By using the machine, wherein the opening and closing of the magnetic circuit are utilized at the same time, a single current is obtained from the two bobbins united in series having a tension double that of each of them, and with the frequency of two periods for each turn.

A more than sufficient space is reserved to said bobbins even for a double winding of 15 high and low tension.

The amplitude of the permeable arc of the rotor is in all cases supposed to be 60° .

We consider firstly the case of shoes 5 having the amplitude of 90° , in the moment 20 where the main axis of the permeable section of one rotor (for instance B; see Fig. 5) meets with the diameter perpendicular to the shoe centre (neutral line).

The electromotive force only begins to be 25 generated when the rotor has turned 15° away from the neutral line, as in said position the core of the rotor is on the point of entering under the polar shoes. From this moment and for the space corresponding to 30 60° the magnetic section progressively increases and, on account of the uniformity of the gap, the increase may be calculated as being proportional to the angle, which is on its turn proportional to the time, by assuming a constant number of turns for the rotor.

Consequently, starting from the moment we have taken at the beginning, the electromotive force will be null for 15° , then constant and negative for the successive 60° (increasing flux).

In the following 30° of rotation, the magnetic section does not vary, the iron core of the rotor remaining fully in front of the polar shoes. There will be a corresponding interval during which the electromotive force is null. As the rotation proceeds still further, the magnetic section (and consequently the flux) decreases according to a law which is uniform as to the time, for the 50 space of 60° , so that a constant and positive electromotive force is generated.

After the exit from the shoe, the iron-core of the rotor, turning on an angle of 15° in the zone of zero flux, comes back to the starting position. In the corresponding interval there is no electromotive force at all. The rotor has described half a turn (180°).

I have graphically illustrated (Figs. 6 and 6^a) what has been said, taking into consideration the fact that in practice, on account of secondary phenomena, the electromotive force will neither be absolutely constant nor void in the said intervals; therefore near the theoretic line with sharp angles, I have 65 drawn a second line with connections and

bends so as to approach the form which is practically assumed by the current.

The synchronous working of the other rotor of the machine shall be now fully described (see Figs. 7 and 7^a).

At the starting moment, when the first rotor (B) has still its axis on the neutral line, the second rotor (B') was at 90° , that is to say with the longest axis of the permeable section on the middle line of the 75 shoes. Upon a rotation of 15° no electromotive force is generated, the flux remaining constant; but as soon as the iron of the second rotor begins to pass the pole shoes, a positive and constant electromotive force 80 is generated which is maintained for the space of 60° .

Then for a space of 30° the electromotive force is null, B' being outside the flux, and for the space of the successive 60° the electromotive force is negative and constant; after 15° of electromotive force null the rotor is again in the starting position (half a turn of the rotor).

By reversing the connection of the bobbin 90 heads it is possible to obtain from the two electromotive forces generated at the same moment, and having the same absolute value but opposite polarities, a double electromotive force having the form shown on Fig. 9^a resulting from the sum of the 7 with the 6 reversed. The maximum of electromotive force resulting from the said addition is reached after a rotation of 45° from the starting position. In relation to the shoes, 100 both rotors, when in the position of maximum of electromotive force, have the iron half facing, half away from the flux, one entering and the other moving away from the same.

Considering now the case of polar shoes of the amplitude of 60° , that is to say of the same amplitude of the permeable arc of the rotors, we assume the same beginning for the times and for the angles and examine the 110 rotor B' (see Fig. 9 and the graph of Figs. 10 and 10^a).

Upon a rotation of 30° the electromotive force is null. For the successive 60° the electromotive force is negative and constant, 115 but there is no more interval of electromotive force null, because the iron comes immediately out from the shoe and generates positive electromotive force for a further space of 60° .

There is then a rotation of 30° in a neutral zone (the corresponding electromotive force being null), before coming back to the starting position. Let us see what happens during the same time as to the second rotor 125 B' (Figs. 11 and 11^a).

At the beginning of the time the flux is maximum and, when the rotation is started, a positive electromotive force is immediately generated which remains constant and 130

of the same polarity for 60° . A rotation of 60° takes place then in a neutral zone with a corresponding interval of electromotive force null.

5. In the successive 60° the electromotive force is negative and constant, returning thus to the starting position.

Here also the connections can be suitably reversed in order to obtain the maximum efficiency of electromotive force.

Figs. 12 and 12^a show the electromotive force resulting from the composition of the 11 with the 10 reversed. It must be remarked that, though the maximum of the 15 electromotive forces produced by the two bobbins be respectively displaced of 60° for the first rotor and of 30° for the second 20 rotor from the origin of the angles the maximum of electromotive force resulting is still produced at 45° from the origin.

In relation to the shoes, the maximum of resulting electromotive force is obtained when the permeable arc of the first rotor B has entered the 15° zone, that is to say for $\frac{1}{4}$ of the amplitude, and when the permeable 25 are of the rotor B' has passed 45° , that is of $\frac{3}{4}$.

In the case of shoes of 90° and the permeable arc of the rotor also of 90° , there will 30 be no more interval of null electromotive force.

What I claim is:

1. In a magneto electric machine delivering pulsating current, one or more rectilinear permanent magnets, and pole shoes connected thereto, in combination with elongated cylindrical rotors each comprising a cylinder of diamagnetic material having a longitudinal slot, and a bundle of plates 40 mounted in said slot, and means for rotating the rotors.

2. In a magneto electric machine delivering pulsating current, one or more rectilinear permanent magnets, pole shoes for said 45 magnets, and two rotors each comprising a cylinder of dia-magnetic material having a longitudinal slot therethrough, and insulated plates in said slot, and means to syn-

chronously rotate said rotors in orthogonal relation.

3. In a magneto electric machine, parallel straight permanent magnets, armatures disposed in planes at right angles to the plane of the magnets, pole shoes connecting like poles of said magnets, and windings between 55 the poles of unlike sign and embracing the middle of said armatures.

4. In a magneto electric machine, a plurality of straight permanent magnets, laminated pole shoe elements at the ends of said 60 magnets, windings included between the elements at one end of the magnets and the elements at the other end, and cylindrical rotors passing through said elements and windings.

5. In a magneto electric machine, a plurality of permanent bar magnets, laminated pole plates arranged in two groups at opposite ends of said bars, windings included between said groups, said plates having 70 alined perforations forming pole shoes, said perforations being in orthogonal relation to the plane of the bars, rotors passing through said perforations and windings, and means to rotate said armatures while maintaining 75 angular displacement.

6. In a magneto electric machine, a field element comprising a plate having perforations for the reception of permanent magnets and perforations in orthogonal relation thereto for armatures, the latter perforations configured to form pole shoes.

7. In a magneto electric machine two sets of iron plates, means to secure the sets together in spaced relation, windings held between the sets of plates, said plates having two sets of alined perforations displaced 90°, bar magnets in one set of perforations and cylindrical armatures in the other set of perforations, said armatures each comprising a cylinder of dia-magnetic material having a longitudinal slot, and insulated laminations filling said slot.

In testimony that I claim the foregoing as my invention, I have signed my name.

MICHELANGELO MARIA CARDELLINO.
